US00D611409S

(12) **United States Design Patent**
Green et al.

(10) **Patent No.:** US D611,409 S
(45) **Date of Patent:** ** Mar. 9, 2010

(54) **POWER ADAPTER**

(75) Inventors: **Chris Green**, San Francisco, CA (US);
John E. Johnston, Redwood City, CA
(US)

(73) Assignee: **Amazon Technologies Inc.**, Seattle, WA
(US)

(**) Term: **14 Years**

(21) Appl. No.: **29/330,620**

(22) Filed: **Jan. 9, 2009**

(51) **LOC (9) Cl.** **13-02**

(52) **U.S. Cl.** **D13/110; D13/138.1**

(58) **Field of Classification Search** .. D13/137.1–137.4,
D13/138.1, 138.2, 139.1–139.8, 107–108,

(57) **CLAIM**

The ornamental design for a power adapter, as shown and described.

DESCRIPTION

FIG. 1 is a top-front perspective view of a power adapter;
FIG. 2 is a bottom-back perspective view of the power adapter of FIG. 1;
FIG. 3 is a front elevation view of the power adapter of FIG. 1;
FIG. 4 is a back elevation view of the power adapter of FIG. 1;
FIG. 5 is a bottom plan view of the power adapter of FIG. 1;
FIG. 6 is a top plan view of the power adapter of FIG. 1;
FIG. 7 is a left side elevation view of the power adapter of FIG. 1; and,
FIG. 8 is a right side elevation view of the power adapter of FIG. 1.
The broken lines in the center of FIGS. 2 and 4 are directed to environment and are for illustrative purposes only. The broken lines form no part of the claimed design.
